CLAIM

The ornamental design for a roofing tear-off machine, as shown and described.

DESCRIPTION

FIG. 1 is a perspective view of a roofing tear-off machine showing my new design;

FIG. 2 is a side elevational view of the right side thereof;

FIG. 3 is a side elevational view of the left side thereof;

FIG. 4 is a top plan view thereof;

FIG. 5 is a front elevational view thereof;

FIG. 6 is a rear elevational view thereof; and,

FIG. 7 is a bottom plan view thereof.
